United States Patent Office

Des. 229,149
Patented Nov. 13, 1973

229,149

NEEDLEPOINT CANVAS

Marcia Podell, 233 E. 69th St., New York, N.Y. 10021

Filed July 8, 1971, Ser. No. 160,990

Term of patent 3½ years

Int. Cl. D6—7.3

U.S. Cl. D6—26a

FIG. 1

FIG. 2

FIG. 1 is a top plan view of a needlepoint canvas showing my new design.

FIG. 2 is a top plan view of a second embodiment thereof, wherein contrast has been indicated.

I claim:

The ornamental design for a needlepoint canvas, as shown and described.
